UNITED STATES PATENT OFFICE.

THOMAS A. B. CARVER, OF GLASGOW, SCOTLAND.

SUPPORTING APPLIANCE.

952,184.

Specification of Letters Patent. Patented Mar. 15, 1910.

Application filed January 8, 1909. Serial No. 471,224.

To all whom it may concern:

Be it known that I, THOMAS ALBERT BRIGGS CARVER, a subject of the King of Great Britain and Ireland, and of 9 Spring-
5 field road, Dalmarnock, Glasgow, Scotland,
have invented certain new and useful Im-
provements in or Connected with Supporting
Appliances, for which I have made ap-
plication for a patent in Great Britain, No.
10 20,310, dated September 28, 1908, of which
the following is a specification.

This invention relates to the construction
of supporting appliances involving the pro-
vision of two rigid rods of rounded forma-
15 tion arranged parallel to one another and
set in a plane in which the pair are capable
of angular adjustment and in which each
rod is capable of independent axial adjust-
ment.

20 According to this invention a chair is pro-
vided in association with a cap between
which the rods are adapted to be gripped,
provision being made for insuring their par-
25 allelism and for drawing the cap and chair
together and for securing them to a struc-
ture to which the support is to be fixed.

In the accompanying drawings some ex-
amples of the construction and application
30 of appliances according to this invention are
illustrated, in which:—

Figures 1, 2, 3 and 4, illustrate some ex-
amples of supporting appliances, Fig. 5 is
an illustration showing some examples of
the application of this invention, and Fig.
35 6 is a sectional elevation and Fig. 7 is a plan
showing a method of fixing a device accord-
ing to this invention.

In the forms of construction illustrated,
with special reference to Figs. 1, 2 and 3 of
40 the drawings, A designates a chair of disk
formation and B a cap having two shoul-
ders B¹ B¹ extending from opposite sides of
a central boss. The chair A and boss of the
45 cap B are centrally bored, and the chair and
shoulders are formed to present opposing
seatings C C¹ respectively to receive two
round rods D D¹ in a plane at right angles
to the axis of the bores of the chair A and
50 cap. E designates a bolt which passes
through the cap B and chair A and through
or into the structure to which the appliance
is to be attached, so that, in tightening the
bolt E, the rods D D¹ are gripped between
55 the cap B and chair A, the chair A being
gripped between the rods D D¹ and the sup-
porting structure, whereby the parts are
locked together. By slackening the bolt E
the rods D D¹ may be adjusted angularly in
60 the plane in which they lie, and also in the
direction of their axes thereby enabling the
length to which the rods shall project from
the clamps to be regulated. To insure an
efficient grip on the rods D D¹ and the par-
65 allelism of the rods, one or both of the seat-
ings C C¹ may be channeled to receive the
rods, the channels being preferably of an-
gular formation examples of which are
shown in the drawings.

gripped between the rods D D¹ and the sup- 55
porting structure, whereby the parts are
locked together. By slackening the bolt E
the rods D D¹ may be adjusted angularly in
the plane in which they lie, and also in the
direction of their axes thereby enabling the 60
length to which the rods shall project from
the clamps to be regulated. To insure an
efficient grip on the rods D D¹ and the par-
allelism of the rods, one or both of the seat-
ings C C¹ may be channeled to receive the 65
rods, the channels being preferably of an-
gular formation examples of which are
shown in the drawings.

In the form of construction illustrated at
Fig. 1, the chair is shown applied to a struc-
ture representing a column F, through
which the bolt E passes, and as an example
of a modified form of construction suitable
for application to a structure, such as a
column F, as represented at Fig. 2, under 70
conditions where it is not desirable for the
bolt E to be passed therethrough, the chair
A is formed with an arm A¹ constituting a
saddle to bear upon the surface of the col-
umn, and a yoke A² is provided for appli- 75
cation to the opposite side of the column,
the fixing of the appliance in position being
effected by the bolt E in conjunction with a
bolt E¹. In action it will be recognized that
in fixing, after the bolt E¹ has been adjusted, 80
by tightening the bolt E, the parts are si-
multaneously locked together as in the form
of construction illustrated at Fig. 1.

In the form of construction as illustrated
at Fig. 3, the chair A is formed to extend at 85
right angles from a base support G which
is adapted to be fixed to the surface of a
structure lying at right angles to the face
of the chair A, in which case, it will be
noted that the bolt E would not act to fas- 90
ten the appliance to the structure. A fur-
ther modification in the construction of such
appliances is to provide two pairs of rods
arranged to lie in planes at right angles to
one another, all capable of independent axial 95
adjustment and angularly adjustable in pairs
independently about a common axis. In the
example of this form of construction as
illustrated at Fig. 4, two pairs of rods D D¹
and H H¹ are provided, and the appliance 100
comprises two central clamps J J presenting
faces between which the pair of rods
D D¹ are adapted to be clamped, the exterior

surfaces of these clamps constituting chairs each furnished with a cap K adapted to bear upon a single rod of the pair H H¹. As shown, the central clamps J J and the caps K K are centrally bored at right angles to their faces, a bolt L passing through the members when assembled, the central rods D D¹ passing on opposite sides and the outer rods H H¹ both passing on the same side of the bolt L, a projecting lug K¹ being furnished on the face of each cap K on the opposite side of the bolt L to that occupied by the rod, in order to present a support for the cap, complementary to that produced by the rod and so prevent its tilting under the action of tightening the bolt L.

In application, the rods of appliances constructed according to this invention are adapted to carry devices, and are particularly suitable for carrying devices under conditions where in the setting, adjustment along the rods is desirable, or where subsequent adjustment is required, giving facility of application and accuracy of adjustment. An example of this application is indicated at Fig. 5 which shows a device M mounted upon the pair of rods H H¹. It will also be recognized that the clamping appliances may be used for fixing pairs of rods to structures, and that clamping appliances as herein described may also be adopted for fixing devices to the rods an example of which is indicated at Fig. 5 in which a device N is shown secured to the two pairs of rods D D¹ by appliances of the form illustrated at Fig. 1, or the appliances may be used for establishing connections between two parts or structures, such, for example, as that shown in Fig. 5 by means of the pair of rods H H¹. The compound association of two pairs of rods is capable of many applications.

In fixing devices to a pair of rods a modified form of clamp may be adopted an example of which is shown at Figs. 6 and 7, comprising a chair A having transverse channeled seatings C the channels being preferably of angular formation, the chair A being formed with segmental slots P near the periphery thereof, for the reception of bolts P¹ adapted to pass through the chair and, say, through a flange of a device R to be fixed to the rods D D¹, the base of the device constituting a cap B, between which and the chair A the rods may be clamped. These rod supports are also particularly adapted for use in supporting bearings, under conditions where the bearings are required to be set and retained in a definite position, the bearing being fixed to the rods by means of suitable clamping devices designed to give the required facilities of adjustment before fixing, an example of which is indicated at Fig. 5, the device M as indicated comprising a bearing for a shaft T. Rods for use in accordance with this inven-

tion, although preferably of circular cross section, may be of hexagonal or other approximately rounded formation.

What I do claim as my invention, and desire to secure by Letters Patent, is:—

1. A supporting appliance comprising two central clamps and two caps in association with two pairs of rigid rods arranged in planes at right angles to one another, the two central clamps presenting faces for gripping one pair of rods and formed to insure the parallelism of the pair of rods gripped, the exterior surfaces of the clamps constituting chairs to act in conjunction with the caps for gripping the other pair of rods, together with means for drawing the caps together, for the purposes set forth. 70

2. A supporting appliance comprising two central clamps and two caps in association with two pairs of rigid rods arranged in planes at right angles to one another, the two central clamps presenting faces for gripping one pair of rods, one of the faces being formed with parallel channels, the exterior surfaces of the clamps constituting chairs to act in conjunction with the caps for gripping the other pair of rods, together with means for drawing the caps together, for the purposes set forth. 85

3. A supporting appliance comprising two central clamps and two caps in association with two pairs of rigid rods arranged in planes at right angles to one another, the two central clamps presenting faces for gripping one pair of rods, the exterior surfaces of the clamps constituting chairs to act in conjunction with the caps for gripping the other pair of rods, together with means for drawing the caps together, for the purposes set forth. 90

4. A supporting appliance comprising two central clamps and two caps in association with two pairs of rigid rods arranged in planes at right angles to one another, the two central clamps presenting faces for gripping one pair of rods, and formed to insure the parallelism of the pair of rods gripped, the exterior surfaces of the clamps constituting chairs to act in conjunction with the caps for gripping the other pair of rods, the clamps and caps being bored axially at right angles to their faces in conjunction with a bolt passing therethrough, for the purposes set forth. 105

5. A supporting appliance comprising two central clamps and two caps in association with two pairs of rigid rods arranged in planes at right angles to one another, the two central clamps presenting faces for gripping one pair of rods, one of the faces being formed with parallel channels, the exterior surfaces of the clamps constituting chairs to act in conjunction with the caps for gripping the other pair of rods, the clamps and caps being bored axially at right 120 angles to their faces in conjunction with a bolt passing therethrough, for the purposes set forth. 125

angles to their faces in conjunction with a bolt passing therethrough, for the purposes set forth.

6. A supporting appliance comprising two central clamps and two caps in association with two pairs of rigid rods arranged in planes at right angles to one another, the two central clamps presenting faces for gripping one pair of rods, the two faces being formed with parallel channels, the exterior surfaces of the clamps constituting chairs to act in conjunction with the caps for grip-

ping the other pair of rods, the clamps and caps being bored axially at right angles to their faces in conjunction with a bolt passing 15 therethrough, for the purposes set forth.

In testimony whereof I have signed my name to this specification in the presence of two subscribing witnesses.
